W. O. LATHROP

BEDSPRING STRUCTURE

Filed Aug. 10, 1921

FIG. 1.

FIG. 2.

FIG. 3.

FIG. 4.

INVENTOR:

Willard O. Lathrop,
by John Elias Jones,
ATTORNEY.

UNITED STATES PATENT OFFICE.

WILLARD O. LATHROP, OF CINCINNATI, OHIO.

BEDSPRING STRUCTURE.

Application filed August 10, 1921. Serial No. 491,259.

To all whom it may concern:

Be it known that I, WILLARD O. LATHROP, a citizen of the United States of America, and a resident of Cincinnati, in the county of 5 Hamilton and State of Ohio, have invented a certain new and useful Improvement in Bedspring Structures, of which the following is a specification.

This invention relates to wire spring-beds 10 in which there are upright helical springs that are coupled together by means of hook-ended strips of wire to support them laterally without interfering with their resiliency or elasticity, and the object of the invention 15 herein is to provide spiral-spring coupling-inserts between assembled groups of the top or upper coils of vertical helical springs and arranging them horizontally in the gap or space lying between adjacent coils of each of 20 said groups of helical springs across the spring-bed bottom, for stabilizing and connecting said helical springs in groups of four and thereby compensating for both the pull and push movements of the said coupling-inserts. 25 This improved structure is designed to form a very economical, simple and easily constructed spring-bed, not easily gotten out of order but readily and cheaply assembled and put in repair when required, and its 30 details will be fully described in connection with the accompanying sheet of drawings, in which—

Figure 1 is a fragmentary plan view of 35 a group or cluster of four adjacent large upper coils of the helical springs used in each unit of an ordinary bed-spring structure, showing my improved spiral-spring coupling-insert in the customary gap or space that lies between them; Fig. 2, a sectional elevation, taken on the dotted-line 2, 2, of Fig. 1; Fig. 3, a diagram containing and showing separately therein the three essential component parts or elements of the 40 spiral-spring coupling-insert of my invention herein; and Fig. 4, a fragmentary elevation showing one of the shepherd-crook ends of one of the coupling-wires of my insert herein, including a cross-section of an upper coil of a helical spring in place therein. 45 5 indicates each one of the usual group or cluster of the top or large upper end-coils of helical springs, (broken arcs thereof only being shown,) and 6 indicates the outer ends of the coupling-inserts used to unite and 50 support the said upper coil-ends of the helical springs in assembled groups across the

mattress or spring-bed bottom. The said outer ends 6 of the wires are preferably bent in shepherd-crook shape and form tempered resilient hooks for the desired snap-hook engagement thereof with the said upper coil-ends of the helical springs, readily engaged and disengaged for assembling the helical springs, or in making repairs when necessary to replace any of such springs, or 60 to provide for breakage. In Fig. 4 I best show the said shepherd-crook engagement with the helical coil-end 5. Said coupling-inserts are each composed of a pair of corresponding Y-shape wire-members and a 70 spiral spring, as shown in the diagram, Fig. 3. The said Y-shape members are each composed of an open or U-shape shank 7 and a pair of forked-arms 8, 8, the latter having at their outer ends 6 the said shepherd-crooks for ready connection with and disconnection from the upper helical coil-ends. 75 Each arm of the fork of a Y-shape member is connected with an upper coil-end 5, so as to connect the coils in pairs, and the shanks 80 7 of the two Y-shape members are brought together in contiguous alinement so that they may slide one in contact with the other, or close to each other, and the spiral spring 9 is placed at the proper time on the engaged 85 pair of shanks 7 so as to encircle them in their sliding-relation, and the opposite ends 10 of the said spiral are turned or tucked inwardly into the bight or nose 11 of the said shanks 7 and thereby used to form stops at 90 both ends of the spiral to prevent its parting or escaping from position on the said shanks 7. The said spiral springs 9 serve to unite the Y-shape members so that their shank-portions may slide longitudinally in 95 opposite directions in contact with or close to each other, the space between the longitudinal legs of the wire in each shank forming a guide-way for the inwardly-tucked ends 10 of the expansion and contraction of the said 100 spirals.

The spiral-spring coupling-inserts herein each contribute toward supporting the helical springs upright and, also, afford or supply the desired elasticity in the bed-structure, for the required surface or horizontal elasticity in the mattress, the helical springs providing or imparting the desired vertical elasticity in the bed. It will be seen that the action of said spiral springs is a torsional as well as longitudinal one, adapted to 110 produce an elastic, resilient and cushioning

effect, and owing mainly to the inwardly-tucked ends thereof in the guide-ways of the assembled shanks 7.

I claim:

- 5 In a bed-spring structure, an elastic torsional coupling-member for each group of four or a multiple of helical springs in the structure, such coupling-member comprising a pair of corresponding forked resilient-wire
- 10 members having fastening-hooks at their forked outer ends adapted to connect with and support the upper coils of respective

grouped helices, U-shape shanks in the said forked members adapted to lie contiguous with each other for sliding-engagement longitudinally along one another, and spiral springs encircling the said slidingly-assembled shanks and having their opposite ends turned inwardly in the guide-ways formed by the said U-shape shanks for coupling the 20 pair of forked members into reciprocating and torsional elastic relation, substantially as and for the purpose specified.

WILLARD O. LATHROP.
